Application August 11, 1939, Serial No. 289,682

12 Claims. (Cl. 250—8)

The dominant characteristic of radio communication is the enormous fluctuation in the ratio of signal to interference; in a short wave link of average difficulty this ratio commonly varies by 70 decibels in the course of a day, and occasionally by much more. A partial remedy for this state of things is to increase the effective power of the transmitter on the one hand, and on the other hand continuously to adjust the characteristics of the traffic so as to keep the percentage of errors sufficiently low; the adjustment consists in varying the speed of working and, when necessary, in repeating telegrams, which is the oldest and best form of the method of diversity. But all these means do not afford a sufficient remedy; when the field intensity of the signal is high and the statics weak, the maximum speed of working permitted by the relays, or by the band width of the link, is well below that which the momentarily favourable condition would in principle allow to be attained; and on the other hand when the signal field is too weak and the interference too intense, it is better to stop traffic altogether than to slow it down excessively. Whence two important consequences:

(a) A rate of working, including repetitions, which is maintained within reasonable limits allows during most of the time considerable traffic speeds while yet affording an unused and excessive margin of safety, but at certain moments, happily brief and rare, becomes impracticable.

(b) The signals issuing from the radio receiver must be deciphered in order to supervise the proportion of errors and correspondingly adapt the radio-electric service to the constantly changing state of the ether, and then must be re-coded to go by wire at the constant speed appropriate to the addressees' printers; this double transformation causes loss of time and substantial expense, the reading and re-transmission of telegrams calling for a numerous specialist personnel; it is besides a source of error, and impairs the secrecy of correspondence since it prevents users communicating directly with each other with apparatus and telegraphic codes of their own choice.

Hitherto it has not been found possible to reconcile a secret and economical terminal service with the optimum output that is obtainable only by constant adaptation to the varying state of the ether. This apparent incompatibility is one of the causes of the high cost of telegrams.

The present invention makes possible an economical, and above all more certain, telegraph service, by re-organizing it with the aid of a combination of improvements all flowing from one

and the same initial achievement that is based on a principle already laid down in my application Serial No. 160,330, filed August 21st, 1937, now Patent 2,176,168, issued October 17, 1939.

This fundamental achievement is a radio receiver which can produce only three effects, dependent on permanent local conditions, such as the thresholds of operation of relays or thermionic tubes; two of these effects will serve to reproduce code signals so long as they are identifiable notwithstanding interference and fading; and nearly all non-identifiable signals will cause the third effect, so that practically no disturbance will cause a wrong signal to be recorded. 15 The invention also permits the use of new codes more complex than those based on two signs only; but its results are then somewhat different and will be considered separately hereinafter. To fix ideas, Figure 1 shows at the top the standard form of the letter *p*, made up of a group of eleven dots and spaces all of the same duration *T*; in the middle of the figure is a distorted record of the letter; at the bottom is the result obtained in accordance with this invention; the eleven elementary signs are there assumed to have been identified and re-constituted save the fourth which is replaced by a dash of length *T* inscribed on a line of uncertainty *x* distinct from the lines *d* and *s* appropriate to the dots and spaces of the code respectively. 20 25 30

As this first result governs the other objects of the invention, the principle on which it rests will at once be explained by the aid of Figures 2 and 3. It is assumed that the receiver supplies to the terminals *O* a rectified current which takes the values *+I* and *-I* in response to dots and spaces of the code received without any interference, and a value *i* varying at random between *+I* and *-I* when, on the contrary, the signal wave 35 40 45 50 55 60 65 70 75 80 85 90 95 is dominated by static; these conditions are approximately realised when a signal wave, frequency modulated to convey the dots of the code by the frequency *F+f* and the spaces by the frequency *F-f*, is received in a filter having these frequencies as the limits of its pass band, is then limited in amplitude, and finally is demodulated by any means which converts fluctuations of frequency into fluctuations of current intensity. A distributor *1*, analogous to that at 69, Fig. 6, is synchronised with another at the radiating station to control the cadence of the signals; it closes the contact *2* for the duration of the sign in course of being received, then closes the contact *3* during a succeeding interval of time of substantially the same duration *T*,

after which the condenser is discharged. While the contact 2 is closed, condenser 4 of capacitance C stores the quantity of electricity supplied by the rectified current; so that at the end of the sign the condenser has acquired one of the voltages

$$+V = +\frac{IT}{C}, \text{ or } -V, \text{ or } v = \frac{1}{C} \int_0^T i \, dt$$

according as the signal has been wholly free from interference or entirely dominated by interference; these are the limiting cases.

It may be seen from Figure 2 that V is necessarily much greater than v; and the probability of the ratio v/V being less than any given proper fraction K, i. e. of the condition $v < KV$ being satisfied, may be made as high as desired; all that is needed is to increase the number of independent values assumed by the current intensity i in the course of an interval of time T, that is to say to increase the ratio T/t between the duration of a code sign and the time constant

$$t \approx \frac{1}{2f}$$

or the filters with which the receiver is equipped; such increase results immediately from a lessening of the speed of working, which factor plays an important part in the present invention as a means of adapting the service to the varying state of the ether; for example, if $t = \frac{1}{400}$ of a second (or the filter has a band width $2f = 400$ c./s.) and $T = \frac{1}{50}$ of a second, there is a 98 per cent chance that the voltage v finally developed by the most intense static will be less in arithmetical value than 0.5 v., that is less than half the voltage V normally developed by a code sign received without interference. At the end of the sign the distributor closes the contact 3; the grid of the tube 5 is then brought for the duration of the next interval to the voltage so acquired by the condenser; relay 6 is adjusted so that it closes contact 7 if this voltage is less than, say, -0.5 v., and closes contact 8 if the voltage exceeds +0.5 v. The grid of tube 9 then acquires the potential D or S for a code dot or space received without interference, and 98 times out of a 100 the potential X if the sign just ended has been entirely covered by interference. The undulator 10, therefore, during the interval of time T during which contact 3 is closed marks a dash along one of the corresponding lines d, s or x on the tape 11, these being the lines already shown in Figure 1. When interference is very intense there remain two chances in a hundred that the voltage of the condenser 4 will have exceeded in arithmetical value 0.5 v. at the instant when the distributor opens the contact 1, and of these one chance in a hundred is that the undulator by chance marks a dash of duration T reproducing the sign just ended, and the remaining one chance in a hundred is that the undulator reproduces the opposite sign which would be an error.

In all, interference dominating the signal wave throughout the duration of a sign will have 98 chances in a hundred of producing the mark of uncertainty x, and one chance in a hundred of causing an error; with an ordinary receiver it would have one chance in two of producing an error. Obviously this case of interference dominating the whole of the sign is the most unfavourable case; in telegraphy by frequency modulation interference of less intensity than the signal wave

is practically innocuous, and does not much alter the voltage +V or -V to which the condenser 4 should be brought at the end of every sign; so the undulator marks the proper dash on the line d or s. The same holds when the disturbing discharge dominates the code sign during only a part of its duration. The important fact to hold in mind is that only three possible events can occur during each closure of contact 3 with the condenser 4 retaining the charge acquired in response to the sign just ended: either this sign is reproduced in its normal form as if the disturbance had not existed, or during the same interval of time T there exists a current x indicating uncertainty, or a real error is produced, current d being recorded instead of current s or vice-versa; but the probability of this error can be made negligible either by separating the contacts of the relay 6 a little, or by reducing the speed of working as required by the state of the ether. A code sign much weakened by fading also causes the recording of a dash of duration T on the line of uncertainty x, so that all accidents produce this same effect.

This first object of the invention alone secures two advantages: The fact that most of the signs have recovered their standard forms enables automatic printers to be used, sensitive as they are to the least irregularity; moreover, error becomes almost impossible for the printer can be built to print a special mark in response to the effect x which does not correspond to any code sign; it is then seen that such and such a letter is simply missing in the text, which is much preferable to the printing of a wrong letter at a point which naturally cannot be located. To these advantages are added two others: (a) a gain of about 9 decibels is obtained in the ratio of signal to interference, as much because the whole quantity of electricity delivered by each sign is accumulated as because the production of rectified currents in accordance with Figure 2 pre-supposes phase or frequency modulated signals which are less sensitive to interference than amplitude modulated signals, and (b) the printer becomes more certain than an undulator marking the fluctuations of the rectified current; for the interval during which contact 2 is closed by the distributor 1 constitutes in effect a preparatory stage which serves by the integration

$$\int_0^T i \, dt$$

to analyse the general run of the rectified current during the sign; it is really a function identical with that performed by an operator carefully examining a record on a tape; but the operator is at a disadvantage for the double reason that the beginning and end of a much distorted sign can often not be discerned by sight, and that the time constants of usual receivers are at least four times less than the duration T of the analysis made by the present process. The judgment that this process renders upon each sign is therefore the most enlightened possible; it is also the most prudent, since in doubt it almost certainly avoids error and marks a sign expressing this doubt; the printer does nothing but give effect to this judgment.

My application Serial No. 160,330, now Patent 2,176,168, already utilised the total accumulation of a rectified current fulfilling the conditions of Figure 2; but after having occupied the position 2 to enable the condenser 4 to be charged the distributor discharged the condenser directly into

the utilising apparatus. This method of operating, represented diagrammatically in Figure 4, did not ensure results corresponding with the mark *a* in Figure 1, namely that the effect derived from the receiver can assume only three values *d*, *x*, or *s*, and once produced this effect remains constant during an interval of time *T* equal to the duration of a code sign. This double condition, necessary for the improvements hereinafter described, necessitates modification of the construction of the distributor and the interposition of a tube 5, the very high grid resistance of which permits the condenser 4 to retain the charge acquired.

The second object of the invention is to discover the percentage of signs impaired by static and fading without the need of deciphering telegrams as they come from the radio receiver; knowledge of this percentage makes it possible to adjust the speed of working to the varying state of the ether. If the code comprises only two signs, this information can be obtained by means of a relay adjusted to close a circuit during only those intervals of time *T* when the distributor 1 (Figure 3) feeds to the tube 5 a difference of potential less in arithmetical value than half the voltage (*V*) normally attained in response to one or other of the code signs; to that end it suffices, in principle, to shift the bias voltages *D*, *S*, making them sufficiently negative to cut off the anode current of the tube 9, so that current flows only under the bias *X*. The time constants of the tube circuits can then be so designed as to average this anode current over a determined interval of time, and this average, which can be read upon a milliammeter, is a measure of the number of impaired signs during this interval. Any signal based on a 2-sign code would serve for this purpose; but as one of the aims of the invention is to organise a service which will permit the public to use codes of its own choice, it is better to discover impairment by the aid of an auxiliary wave emitting dots and spaces alternately at a constant cadence. This wave will also facilitate neutralisation of frequency drifts and synchronisation of the receiver distributors with those of the transmitter.

The present invention also permits the use of 3-sign codes, for instance that in which the dots, spaces and dashes of the alphabet are transmitted by giving the signal wave the frequencies *F*−*f*, *F*, and *F*+*f*. The corresponding results in Figure 3 are then −*V*, *O*, and +*V* for the potentials fed to the grid of tube 5 when the distributor 1 closes contact 3, and *s*, *x* and *d* for the positions taken by the recording apparatus. As in ordinary receivers intense interference and fading now produce the same effect *x* as one of the code signs; nevertheless the present process acquires or retains the two following advantages: the new code enables more words per minute to be transmitted on the same band width, a speed of 100 bauds, i. e., 100 signs or spaces of *T* duration per second, delivering about 150 words per minute in Morse, about 200 in Baudot code, and about 300 with a three sign code; moreover the working of the printers is much more reliable thanks to the rarity of impaired signs and the perfect reconstitution of the rest. In fact, the degrees of safety obtained with codes of two and three signs respectively differ only in this, that in the former impairments appear as a mark of uncertainty, while in the latter they make an error. This difference may make two sign codes preferable for cipher

messages in which a blank that can be located is preferable to an error which cannot be located, while three sign codes are suitable for messages in clear, the reading of which is not hindered by the presence of a few errors. The radio-electric service will moreover be so organized as to permit users to follow their own preferences.

It is proposed further to extend the use of repetition which permits correction of blanks or errors by comparison of two successive records of the same signal. This well known method brings in the time factor, the advantage of which is to diversify both fading and interference; but it implies that disturbances affect only one of the two code signs, so that the other sign may be considered correct if it appears on one of the records. Now this advantage is not fulfilled in ordinary receivers, for their response to fading is the inverse of their response to static. By causing these two phenomena to produce the same effect, namely to mark a dash on the reference line *x* of Figures 1 and 3, the present invention removes this inconvenience; moreover a comparison of records becomes possible whatever the number of signs in the code, since at most only one of these signs normally marks dashes on the line *x* also; everything recorded on the other lines in the course of one of the transmissions is necessarily correct. The following advantage is thus attained; as each record comprises no more than three constituent elements, namely dashes of the same duration *T* inscribed on one of the lines *d*, *s* or *x*, these records can be brought into physical coincidence, or even be superposed upon a single tape; then, at any later time, everything recorded on the lines of this tape can be read automatically. For instance, it can be read by photo-electric cells, like those in use for the reading of facsimile, connected in such fashion as to modulate the frequency of a telephone current actuating the addressee's printer. This principle is illustrated in Figure 5, which shows two different distorted records of the latter *r*, and below the result of superposing them; for the cells 12, 13 reading the lines *d* and *s* respectively, the record has become correct.

The two successive records can be made to coincide as follows; at the transmitter the perforated tape passes in succession through two Wheatstone transmitters *W*₁, *W*₂, one of which impresses on the carrier wave the frequencies *F*₁±*f* and the other the frequencies *F*₂±*f*; at the receiving station two receivers select these respective frequencies and actuate two undulators *o*₁, *o*₂, the tape taking as long to pass from *o*₁ to *o*₂ as the transmitting tape takes to pass from *W*₁ to *W*₂; these time intervals can be equalised once for all, since the speeds of travel of the tapes can be controlled by the synchronised distributors which control the cadence of the signs at the two stations; thus a sign already inscribed by the undulator *o*₁ in response to the Wheatstone transmitter *W*₁ comes beneath the undulator *o*₂ at the instant when it is repeated by the Wheatstone transmitter *W*₂. The undulators must also mark upon the same lines *d*, *x*, *s*, but that condition is easily fulfilled since it depends on simple abutments. Naturally, instead of the undulators, perforators could be used adapted to re-act to the three intensities which the tube 9 of Figure 3 can provide. This method of automatic comparison of the records imposes no limiting condition upon them, and leaves the parties communicating entirely free

to use such printers and such codes as they prefer. Nor does it call for immediate comparison of two transmissions, since the tapes with the two superposed records can be stored until a telephone or other line is available.

The methods just explained all depend on the existence at the receiving station of a distributor synchronised with that of the sending station. Now the analysis and reconstitution of the code signs on the principle illustrated in Figure 3, and the correction of blanks or errors by comparison of successive records, are an improvement in transmission equivalent to a gain of many decibels in the ratio of signal to interference. This gain is conditioned by the synchronising of the distributors, but the synchronisation itself does not benefit from it; it must therefore have a wide margin of safety. It must also be made compatible with variation of the speed of working, by which the radio-electric service is adapted to the varying state of the ether. This two-fold condition would not be satisfied by occasional impulses, as used in the Baudot system in which of twenty-one consecutive signs only one is allotted to synchronisation. This consideration leads to the synchronising of the distributors by means of an auxiliary pilot wave, frequency modulated to transmit a succession of alternate dots and spaces of the same cadence as the code signs. Demodulation of this wave at the receiver gives an alternating current of period $2T$ upon which the motor driving the local distributor can be very rigidly locked. It is then possible to vary the speed of working at the transmitter by varying the speed of the distributor with which the Wheatstone transmitters are located; the synchronised apparatus at the receiver will follow these variations so long as they are sufficiently gradual. The pilot wave performing this function is that already serving to measure the percentage of signs impaired by fading and interference.

Recapitulating the above, the radio-electric service is made more reliable by the use of frequency modulated signals, by the utilisation of the whole of the current supplied by the detector, and most especially by a method which involves for each sign first a more perfect analysis then examination of an undulator tape, and then a nearly infallible decision the effect of which is to reconstitute identifiable signs in their standard form and to make a special mark for signs which cannot be identified. This method makes the printer more reliable than the undulator; it replaces errors which cannot be located by easily located blanks, much fewer in number, and it permits automatic comparison of two successive records of the same signal to correct defects whatever be their cause; this comparison is a direct comparison of the currents fed from the receiver and imposes only one restriction upon the code, namely that it shall be analysable into signs of the same duration. Moreover, the radio service is accelerated both because interference causes less trouble and because new and faster codes can be employed. Communication between two correspondents no longer involves intermediate deciphering and re-coding; the percentage of defective signs is in effect given by an automatic indicator; the signs marked on the tape can be reconverted into currents which for the reasons already explained are adapted for the actuation of printers; the storage of tapes affords the time needed to wait for a line to become available and to allow for the difference of practice between the radio electric service and the terminal service.

The addresses of the addressees alone (until automatic directors are available) need be read at the receiving station, but that does not detract from the advantages due to direct utilisation of the records produced by the radio receiver.

Successive transmissions of a signal on two frequency bands can be obtained, when circumstances call for it, by twinning two channels of a multiplex system. Such a system is both 10 economical, since buildings, land and antennae are common to all channels, and flexible since the channels can be employed at will either singly or two by two. For instance, two of them can be permanently associated to ensure maximum 15 reliability in the transmission of cipher on two sign code, while the rest work sometimes singly and sometimes two by two to deal with traffic in clear on three sign codes. Thus in one and the same station a scale of reliability is obtained having steps enough to satisfy all requirements. A band width of 3,000 cycles makes seven 20 channels possible, one for the pilot wave, and others for traffic; in three sign code the maximum output of this scheme exceeds 2,000 words per minute. Considering the degree of reliability 25 already attained in telegraphy, in which interruption due to natural disturbances are rare, experiment proves that there is little gained by increasing the power radiated; the greater reliability which the present invention affords will therefore preferably lead to diminution of the radiated power, and consequent reduction in the power of the machines, in the cumbrousness of aerials, and in the area of land occupied.

35 Figures 1 to 5 have served to illustrate the explanation above.

Figure 6 illustrates the construction of a telegraph system according to the present invention.

Figures 6a, 6b, 6c, 6d and 6e serve to explain 40 various details of Figure 6, and

Figure 7 shows, in an alternative embodiment, the control of a magnetic recorder.

Figure 6 concerns the general organisation of 45 a multiplex telegraphy system between a local and a distant correspondent. The apparatus of the local service are illustrated in detail, while those similar to these, at the distant correspondent, are simply recalled by the same references followed by the index *a*. In one direction and the other, there may be any suitable number of 50 channels; in the figure, three channels have been indicated in each direction, viz. the first reserved for the pilot wave, while the other two serve, separately or in combination, for the transmission of the communications. The local transmitting antenna 14 thus radiates three waves, the frequencies of which vary respectively between F_1-f and F_1+f , F_3-f and F_3+f , F_5-f and F_5+f , while the local receiving antenna 15 receives those emitted 55 by the distant correspondent on the bands $F_2\pm f$, $F_4\pm f$ and $F_6\pm f$. The duration of all code signs transmitted by the local station and by its distant correspondent are denoted respectively by T_1 and T_2 . The right hand side of the figure concerns 60 the local central telegraph station, where the traffic arriving by wire is transformed to modulate the transmitter, and that received by the radio receiver undergoes the converse transformation for being transmitted by wire to the final addressee. The central part of the figure represents above, the local radio transmitter, the parts of which bear the references 22 to 52 and 14, and below, those of the local radio receiver. The 65 left hand side of the figure shows broadly the

arrangement of the similar parts at the distant correspondent.

At the central telegraph station lines 16 are joined as desired by means of connectors 17, 17', to perforators such as 18, 18', which may be operated by users from a distance by the sending of proper currents. The perforated tapes pass either through the Wheatstone transmitter 19 which when switch 20 is on contact 21 controls the frequency of the $F_1 \pm f$ channel by means of relays 22, 23, or in succession through the Wheatstone transmitters 24, 25, one of which, 24, always controls the frequency of the $F_3 \pm f$ channel by means of relays 26, 27, while the other, 25, may control the $F_1 \pm f$ channel when switch 20 is on contact 28. In the second case the same signal is transmitted first by transmitter 24 on the $F_3 \pm f$ channel and then by transmitter 25 on the $F_1 \pm f$ channel; the time interval between these transmissions is the ratio of the distance L between the transmitters to the speed of travel of the tape 29; the distance L is a constant chosen once for all, say as equal to the length of tape occupied by one hundred code signs; the speed of travel of the tape is determined by the toothed wheel 30 driven by the motor 31 which thus regulates the cadence of the code signs. This cadence is made manifest at the receiving antenna 15a of the distant station by the emission of an uninterrupted succession of dots and spaces of duration T_1 , translated into the frequencies F_5+f and F_5-f of the pilot channel; for this purpose a distributor 33, also driven by the motor 31, controls the relay 34. A rheostat 35 serves for adjusting the speed of the motor and therefore the common cadence of the transmitters 19, 24, 25 and distributor 33; the use of a tangent screw 36 to adjust the rheostat necessitates the adjustment being made sufficiently gradually to be easily followed by the synchronised distributor at the distant receiver. A key 37 enables service messages to be sent through the channel $F_1 \pm f$ if switch 20 is put on contact 38.

The local radio transmitter comprises a master oscillator 39 of frequency F_0 , which together with generators 41, 43 and 45 excites a modulator 49. These generators are made of fairly low frequencies, and their frequencies vary, in response to variation in the impedance of tubes 42, 44, 46, above and below mean values f_1 , f_3 , f_5 which are separated by the desired intervals F_5-F_3 and F_3-F_1 between the three channels. The variations of impedance of the tubes are brought about by relays which vary their grid bias; for instance the generator 41 has its mean frequency f_1 when relay 22 applies the mean bias, and its extreme frequencies f_1-f and f_1+f according as the contacts of both relays are open, or the contact of relay 23 is closed; the amplitude f of the variations so obtained can be adjusted by simultaneous shifting of the tappings 47, 48 one on each side of the tapping which gives the mean bias. Only the relay 23 is in use to give the extreme frequencies required for a two sign code; the relay 22 gives in addition the intermediate frequency needed for three sign codes. The frequency of the second channel is controlled in the same way by relay 21, and, if required, by relay 26. Since it uses only two frequencies, the pilot channel has only the relay 34, the effect of which can also be adjusted by shifting the bias tappings 49, 50. The filter 51 sorts out one of the bands produced in the modulator 49 by the addition and subtraction of the frequencies $f_1 \pm f$, $f_3 \pm f$, and $f_5 \pm f$ to and from the frequency F_0 . Oscillations in this band are amplified at 52,

radiated by the antenna 14 and collected by the receiving antennae 15a of the distant station.

The waves radiated by the transmitting antenna 14a of this distant station are similarly collected by the local receiving antenna 15, and after amplification in the HF amplifier 54 are reduced in frequency in the frequency changer 55 in which they are heterodyned with oscillations from the oscillator 56. The filters 57, 58, 59 select respectively the two signal waves $F_2 \pm f$ and $F_4 \pm f$ and the pilot wave $F_6 \pm f$ which last is modulated by the distant station to the cadence of its code signs of duration T_2 . Consider first communication upon the middle frequency F_4 ; as Figure 6a shows, the band selected by the filter 58 is centred on this frequency F_4 , and to allow for the speed of working its width is a little greater than the sum $2f$ of the frequency variations into which the signs are translated. After selection, the signal wave passes through a limiter 60 which stabilises its amplitude save when fading is exceptional. The fluctuations of frequency which now alone subsist are transformed into fluctuations of a voltage u ; this can be done in various ways, for instance as described in my United States Patent No. 1,612,101 patented December 28, 1926; that method employs two resonators 61, 62 tuned to the frequencies F_4-f and F_4+f respectively, which supply detectors 63, 64; allowing for the filter 58 the output voltage u of this demodulator is a function of the frequency of the form shown by the line 2 of Figure 6b; hence it has the value $+U$ for code dots translated into the frequency F_4+f , the value $-U$ for spaces, and is zero for the third code sign, if there be one, received on the mean frequency F_4 . Fading too severe to be neutralised by the limiter also tends to bring this voltage to zero. As to oscillations due to statics, they are indifferently any frequencies passed by the filter 58, so that in response to interference u varies at random between the limits $+U$ and $-U$; these are the conditions already illustrated by Figure 2 in connection with the theoretical explanation of the invention.

The variations of voltage u are transmitted to amplifying tube 65, preferably placed at the central telegraph station, and the output current i of this amplifier takes the values $+I$ and $-I$ in response to the frequencies F_4+f and F_4-f . Each of the condensers 66, 67 in turn receives the quantity of electricity represented by this current flowing for the duration of a code sign, and then in the next succeeding interval of time T_2 applies to the grid of the tube 68 the potential v resulting from this charge; thus the condenser 66 deals with every other sign, and the condenser 67 with the intervening signs. They are caused so to operate by the distributors 69, 70, the brushes 71, 72 of which are displaced in relative phase by 180° , and are driven by the synchronous motor 73 at the rate of half a revolution per time T_2 . Figure 6 shows them in the position they occupy at the beginning of a code sign which is going to be recorded by the condenser 66. At this initial instant, the condenser is short-circuited by the small sector 74, and so is brought to neutral condition. Soon after the beginning of the sign the brush contacts with the sector 75 and remains in contact with it nearly to the end of the sign; during this time the condenser receives the quantity of electricity supplied by the current i , and stores practically the whole of it since the time con-

stant of the circuit 66, 76 is made substantially greater than T_2 ; the sector 75 is made to extend over a little less than a half circle to allow for possible slight errors in the setting of the synchronous motor 73. So the brush leaves the sector 75 a little before the end of the sign and at once contacts with the sector 77; the grid of tube 68 is then biased to the voltage v acquired by the condenser, and this voltage remains constant since the condenser is practically on open circuit, and the bias is maintained during an interval T_2 because the sector 77 extends over a semi-circle. When the brush leaves this sector the recording of the sign is finished and the brush 72 then contacts with the sector 78 of the other distributor so as to apply to the grid of the tube 68 the voltage acquired by the condenser 67, thus recording is perfectly continuous; the resistances 79, 80 prevent the condensers appreciably discharging the one into the other should the sectors 77, 78 be in circuit together for an instant. It has already been shown that the voltage v normally reaches the values $+V$ or $-V$ in response to code signs translated into the frequencies F_4+f and F_4-f , and has a value almost certainly less than 0.5 v. when statics dominate a sign from its beginning to its end. Relays 81, 82 are therefore set the one to close contact 83 for voltages less than -0.5 v. the other to close contact 84 for voltages greater than 0.5 v.; such setting is illustrated by Figure 6c where the position of the contacts is plotted on a scale of potentials. So as long as the sector 77 or 78 is in circuit one or other of the three following effects is obtained; either a code sign just received without notable interference on frequency F_4-f brings about the closing of contact 83, the biasing of the grid of tube 85 to the potential 86, the excitation of relay 87 and the attraction of its armature 88 to extreme position, so that the siphon 89 of the undulator marks a dash of exactly duration T_2 on the reference line s ; or a code sign received on frequency F_4+f brings about the closing of contact 84, the biasing of the grid of tube 90 to the potential 86, the attraction of its armature 92 by relay 91 and the shifting of the undulator to the line d ; or, finally, a sign, either much distorted by statics or fading or represented by the mean frequency F_4 brings about the opening of both contacts 83, 84 and the biasing of both tubes 85, 90 to the much more negative potential 93, with the result that neither of the relays 87, 91 is excited, and the siphon, withdrawn by its spring 94, comes to rest upon its abutment 95 and marks a dash of duration T_2 on the line of uncertainty x . These lines s , d , x are perfectly definite; instead of actuating an undulator the relays 87, 91 could obviously cause blows upon a ribbon like a typewriter ribbon.

After selection by the filter 57 the signals of the $F_2 \pm f$ channel are demodulated and recorded in the same way, either on the undulator 96 if they are independent signals, or on the undulator 97 if they are a repetition of the signs already transmitted on the $F_4 \pm f$ channel. For the purpose of such repetition the distant station has two Wheatstone transmitters like those 24, 25 in the local central telegraph station. Since they are both composed of dashes of duration T_2 inscribed on the lines d , s or x , the successive records are superposed, subject to accidental defect, provided the tape 98 takes as long to pass from the undulator 89 to the undulator 97 as the transmitting tape takes to pass from one Wheat-

stone transmitter to the other; once established, the identity of these time intervals is maintained indefinitely since the driving member 99 of the receiving tape is connected with the motor 73 which itself is synchronized with the motor driving the transmitting tape. Figure 5 showed an example of the result obtained by superposing the two successive records.

Insofar as connections can be established with the addressees by the lines 16, the tapes are automatically read either by facsimile apparatus if recorded by an undulator or by Wheatstone transmitters if the relays such as 87, 91 have been used to perforate the tape along the lines s , d , x . The figure illustrates the first arrangement; two photo-electric cells 100, 101 translate the dashes inscribed on the lines d and s into currents which, after amplification at 102 and 103, actuate the relays 104, 105 respectively. The excitation of relay 104 applies to the grid of tube 106 a voltage of audio frequency derived from the generator 107, and the resulting anode current of the same frequency is transmitted by transformer 108 to the line; the excitation of relay 105 similarly transmits a current of another frequency determined by the generator 109; the dashes inscribed along the line x are translated into interruptions of the current. Thus the addressee's printer receives three indications, two representing code signs and the third representing either uncertainty or a supplementary code sign.

The pilot wave, the frequency of which is periodically varied by the distant station from F_6-f to F_6+f to mark the cadence of his code signs can serve in the local station to synchronize the motor 73 with this cadence, to control amplification, to neutralise the frequency drifts, and automatically to indicate the percentage of imperfections due to interference or fading. After selection by the filter 59, the selected band of which is illustrated by g in Figure 6d, this pilot wave first controls the HF amplification by means of the rectifier 110 and the lead 111; there is nothing special about this control; it should however, be slow enough not to follow selective fading which does not affect the several channels at the same instant. The wave is then stabilised in amplitude by the limiter 112, then demodulated by means analogous to those already described but adjusted in a slightly different way; its resonators 113, 114 are tuned, not to the frequencies of modulation, but to two frequencies F' and F'' just outside the bounds of the filter 59; the output potential difference u' of the demodulator then varies almost linearly from one boundary to the other, as seen in Figure 6e; its values $-U'_1$ and $+U'_2$ obtained in response to the frequencies F_6-f and F_6+f cease to be equal and opposite if there is any frequency drift, and their mean is no longer zero. This property makes it possible to neutralise drifting of the heterodyne oscillator 56; the mean of the voltage u' obtained by means of the high time constant circuit 116, 117 is applied to the grid of the tube 115; when this mean value ceases to be zero, the armature of relay 118 closes one of the contacts 119 or 120, so modifying the charge of the condenser 121, the bias on the grid of the tube 122, and therefore the anode impedance of that tube; if the connections are made in the right sense this variation of impedance corrects the frequency of the oscillator 56 until the mean of the voltage u' becomes zero again and the armature of the relay resumes its position mid-way between the con-

tacts; the condenser 121 then keeps the charge it has temporarily acquired until a fresh correction becomes necessary.

The variations of the voltage u' are transmitted to the tubes 123, 124, preferably placed at the central telegraph station to control on the one hand the percentage impairment indicator and on the other hand the locking of the motor 73 to the cadence adopted for its code signs by the distant station. The current derived from the anode of tube 123 is an alternating current of period $2T_2$, since the antenna 14a transmits alternately dots and spaces of duration T on the frequencies F_6+f and F_6-f respectively; it would be possible to amplify this current and control by it a synchronous motor driving the distributors such as 69, 70, the arrangement shown in the figure has the advantage of obviating all slip; the motor 73 drives a generator 125 which supplies alternating current that has also the period $2T_2$ when the speed of the distributors is correct; the currents delivered by this generator and by the tube 123 interfere in the detector tube 126, with the known result of producing in the anode circuit of that tube an interference current the intensity of which depends on the difference in phase between the two alternating currents; the relay 127 is adjusted so that its armature is balanced between the contacts 128, 129 for a difference of phase of, say, 90°; any departure from this value closes one of the contacts, and, through the medium of the amplifying tube 130, modifies the excitation of the motor and therefore its speed; the rate at which such corrections are brought about is made greater than the rate at which the distant station can adjust the cadence of its signs by adjustment of a rheostat like the rheostat 35, 36 shown at the local central station.

The automatic counting of impairments due to fading and statics is effected by the aid of tube 131, the grid of which may be connected by a switch 132 either to the distributors 133, 134 of the pilot channel, or to the distributors 69, 70 of one of the signal channels; the latter must, however, in this case employ a two sign code, so that the voltage v applied to the grid of the tube 131 normally takes only two values $+V$ and $-V$. Differing from the scheme of relays 81, 82, here it is the simultaneous closing of the contacts 135, 136 of which use is made, this occurring when the voltage v falls by chance between the values -0.5 v. and $+0.5$ v. Each closing of the contacts, caused by the distributors to last a uniform time T_2 , tends to bring the bias of tube 137 from the value corresponding to the tapping 138 to the less negative value corresponding to the tapping 139; but this change of bias is limited by the charge which the condenser 140 can acquire through the resistance 141 during this brief interval of time T_2 , to which therefore the change of bias is proportional. Increments of charge each proportional to T_2 so acquired by the condenser 140 as successive impairments occur, accumulate insofar as the continuous slow discharge of the condenser through the high resistance 142 permits, for in normal conditions one or other of the contacts 135 or 136 is open nearly all the time. Thus the grid bias finally acquired by the tube 137 at any given instant is nearly proportional to a ratio the denominator of which is the time constant of the circuit 140, 142, and the numerator the total duration $N \cdot T_2$ of the N successive impairments that have occurred during an interval equal to this time

constant. N is the sole unknown in this ratio; the milliammeter 143 which measures the grid bias of tube 137 may therefore be graduated by calculation to indicate directly the number N of impairments which have occurred in a given lapse of time, say 20 seconds. This information enables the supervisor of the local service to give the distant transmitter directions as to the speed of working, and if necessary for the repetition of signals. Such orders are transmitted by the key 37 shown beside the indicator 143.

In the same way, the local service receives from the distant station orders concerning the adjustment of the rheostat 35 which controls the cadence of the signs, and of the switch 20 by which repetition is set in train when required. Such orders come, for example, through the $F_2 \pm f$ channel, and are translated into variations of potential applied to the grid of the tube 144; in response to these variations the relay 145 applies to the grid of tube 146 a more or less negative bias which cuts off or re-establishes the anode current of that tube. This current, made audible by the audio generator 147, actuates the loud speaker 148 shown beside the rheostat 36.

Various detail modifications may of course be performed in the device of Figure 6 without departing from the frame of the invention.

For instance, the marks made on the reference lines d, s, x by the currents issued from the receiver could be traced on rolls of sensitive paper similar to those used in fac-simile receivers.

According to another alternative embodiment, illustrated in Figure 7, the three effects which may be set up by the receiver are materialised no longer visually on three lines, but magnetically by recording a frequency and/or amplitude modulation on the steel wire of a magnetic recorder: The tube 68 and the relays 81, 82 are those already represented in channel $F_4 \pm f$ of Figure 6; the closing of contact 83, obtained when the voltage v delivered by the distributor to the grid of this tube is less than -0.5 v., subjects the grid of tube 149 to a bias of musical frequency f' supplied by the source 150; the closing of contact 84, obtained when $v > 0.5$ v., sets up a bias of a different frequency f'' supplied by the source 151, while the simultaneous opening of contacts 83, 84, obtained when v lies between -0.5 v. and $+0.5$ v. will carry the grid of tube 149 to the permanent bias 93, which may be sufficiently negative for suppressing the anode current of this tube. The electromagnet 152 will therefore be subjected, at the end of each sign, to one of the following three effects, which, by the synchronous distributors, are imposed for the constant duration T_2 : a current of frequency f' representing one of the code signs, a current of frequency f'' representing the second sign, and a constant or zero current expressing the state of uncertainty and further capable of representing the third sign of a three sign code. This frequency and amplitude modulation alters the magnetisation of the steel wire 153 driven by the wheel 93 connected with the synchronised motor 73. As before, the signal may be repeated over the channel $F_2 \pm f$, in which case the terminal electromagnet of this channel, 154, will confirm the magnetic recordings already set up by the electromagnet 152 or fill up the places which may have been left empty, represented by the regions of the wire where the magnetisation had remained constant during the first transmission. At any subsequent moment, the magnetisation variations may be retransformed into current varia-

tions capable of actuating the printers, after which the wire is brought back to the neutral state in order to permit the recording of new signals.

In short, the process may serve for materialising the received signals, in a manner to permit their correction by repetition, and then their storing until a line for transmitting them further has become free.

What I claim is:

1. A system for telegraphic communication by codes built up of grouped signs of unit length, which comprises, means for demodulating the received wave so as to transform this wave into a current of varying intensity, means for substantially accumulating the electricity supplied by this current over each unit length, means responsive to the result of this accumulation for producing at the end of this unit length one of three definite effects, two of said effects normally representing two of the code signs while the third represents as indifferent condition of known significance, means for maintaining each of said produced effects over a following unit length, and means for utilizing this effect while it is thus maintained.

2. In radiotelegraphic communication liable to disturbances such as fading and static, and utilizing codes made up of two distinct signs of unit length, a receiver which comprises, means for demodulating the received wave so as to transform this wave into a current of varying intensity, means for substantially accumulating the electricity supplied by this current over each unit length, means responsive to the result of this accumulation for producing at the end of this unit length one of three definite effects, two of said effects normally representing the respective signs and the third representing either disturbed sign, means for maintaining each produced effect over a following unit length, and means for utilizing this effect while it is thus maintained.

3. In radiotelegraphic communication liable to disturbances such as fading and static, and utilizing codes made up of three distinct signs of unit length, a receiver which comprises, means for demodulating the received wave so as to transform this wave into a current of varying intensity, means for substantially accumulating the electricity supplied by this current over each unit length, means responsive to the result of this accumulation for producing at the end of this unit length one of three definite effects, two of said effects normally representing two of said signs respectively and the third representing the third normal sign and any disturbed sign, means for maintaining each produced effect over a following unit length, and means for utilizing this effect while it is thus maintained.

4. A radio telegraphic system for codes based on the grouping of signs of equal duration comprising a transmitter radiating a signal wave modulated in response to these signs, a receiver, means responsive to the combined action of the transmitter and receiver to produce in the output of the receiver a current the intensity of which assumes two constant values in response to two of the code signs respectively and varies at random between these values in response to statics and fading, a distributor synchronised with the cadence of the signs to accumulate while each sign lasts the quantity of electricity conveyed by said current and then to maintain and utilise during an interval of time equal to

the duration of the sign the voltage due to such accumulation, voltage-controlled apparatus having two thresholds of response beyond the voltages which can be produced by the accumulation of variable current due to statics, and means for obtaining from this apparatus three definite effects of the same duration, two of said effects being obtained when the voltage reaches one or other threshold of response respectively, while the third effect is obtained when neither threshold is reached.

5. In radio telegraphic communication by codes based on the grouping of signs of the same duration, individually represented by a particular frequency of the signal wave, a receiver including a selective filter selecting substantially the band upon which the communication is transmitted, a demodulator which transforms variations in frequency on one side and the other of the middle frequency of the filter into variations in intensity of current, so that in response to statics said current takes any intensity intermediate between those corresponding to the limit frequencies of said filter, two condensers, a vacuum tube with a control electrode, two distributors synchronised with the cadence of the code signs and associated with said condensers respectively so as each in turn to perform within the duration of two code signs three consecutive operations, the first of short duration being to short circuit the condenser to discharge it prior to the sign about to begin, the second operation occupying nearly the whole duration of this sign and consisting in the accumulation in the condenser of the charge supplied by the current, the third operation occupying a time exactly equal to the duration of every sign and consisting in applying to the control electrode of said tube the voltage resulting from the charging of the condenser, a system of relays actuated by said tube and adjusted to close two contacts, one for the voltages a little below and the other for voltages a little above the extreme voltages which the condenser can acquire from the variable current due to statics, and means for obtaining from said relay system one of three effects, two of them corresponding respectively to the close of one or the other of the contacts and the third to the simultaneous opening of both contacts.

6. In radio telegraph communication in which the receiver at the end of each sign can produce one of only three definite effects of the same duration, of which two normally represent two of the signs and the third represents an indifferent condition of known significance, the method of correcting errors due to statics and fading, which consists in feeding a message tape to a transmitter repeatedly for transmitting the same signal a plurality of times, in recording the successive effects obtained in response to each transmission, in making the records coincide for comparison, and in scanning the coincident records so as to translate them into their corresponding intelligence by rejecting recordations of the third effect where a recordation of any one of the other effects is concurrent therewith.

7. In radiotelegraphic communication in which the receiver at the end of each sign can produce one of only three effects of the same duration, of which two normally represent two of the signs and the third represents an indifferent condition of known significance, the method of correcting errors due to statics and fading, which consists in feeding a message tape

to a transmitter repeatedly for transmitting the same signal a plurality of times, in marking a record tape in three lines, corresponding respectively to said three effects, in accordance with the effects obtained in response to each transmission, in making the records coincide for comparison, and in scanning the coincident records so as to translate them into their corresponding intelligence by rejecting recordations of the third effect where a recordation of any one of the other effects is concurrent therewith. 10

8. In radio telegraphic communication in which the receiver can only produce at the end of each code sign one of three effects of the same duration, two of said effects normally designating two signs and the third designating an indifferent condition of known significance, the method of repetition for correction of errors which consists in feeding a message tape to a transmitter repeatedly for transmitting the same signal a plurality of times and at convenient intervals of time, in marking a record tape in three lines, corresponding respectively to said three effects, successively in accordance with the effects obtained in response to each transmission, and passing said tape from one recording position to a succeeding recording position in a time equal to the interval between the corresponding transmissions, so that the records are superposed on the tape save for distorted signs which are all recorded on the line corresponding to said third effect.

9. A system applicable to radio telegraphic communication for automatically discovering distortion due to disturbances such as fading and statics, comprising means for producing in the receiver output a definite effect in response exclusively to such disturbances and means connected with the aforesaid means for summing such effects over a determined interval of time. 35

10. A system applicable to radio telegraphic communication for indicating automatically the seriousness of trouble due to disturbances such as statics and fading comprising means for producing in the output of the receiver a current of constant intensity and duration in response to each code sign distorted by disturbances exclusively, so that each distortion is represented

5 by the production of a definite quantity of electricity, a circuit including a condenser and a resistance, said condenser being connected with said means and operative for accumulating the definite quantities of electricity produced during an interval of time equal to the time constant of said circuit made up of said condenser and said resistance, and means for indicating the voltage acquired by the condenser as the result of such accumulation as an index of the effects of statics and fading.

11. In radio telegraphic communication by codes based on the grouping of signs of the same duration following each other in a definite cadence, apparatus for enabling variation of the cadence comprising at the transmitter means for generating an auxiliary wave, for modulating said wave at a frequency which is a function of the cadence of the signs, and for impressing 20 at will upon the cadence gradual variations the rate of which is limited, and comprising at the receiver means for converting the auxiliary wave into an alternating current of the frequency of modulation of the wave, local distributors operative at the cadence of said signs, a motor for driving the local distributors, and means for synchronising said motor with said current, said synchronising means having a time constant related to the limiting rate of variation of the cadence at the transmitter.

25 12. In radiotelegraphic communication liable to disturbances, such as static and fading, and utilizing codes made up of grouped signs of unit length, a receiver which comprises means for demodulating the received wave so as to transform this wave into a current of varying intensity, means for substantially accumulating the electricity supplied by this current over each unit length, means responsive to the result of this accumulation for producing at the end of this unit length one of three definite effects, two of said effects normally representing two of said signs respectively while the third represents an indifferent condition of known significance, and means for collecting the produced 40 45 effect over a following unit length.

HENRI JEAN JOSEPH MARIE DE
REGNAULD DE BELLESCIZE.
